UNITED STATES PATENT OFFICE.

EDWARD L. WELLS, OF MACOMB, ILLINOIS, ASSIGNOR TO AMERICAN STEEL PRODUCTS CO., OF MACOMB, ILLINOIS, A CORPORATION OF ILLINOIS.

OIL-BURNER-CONTROL MECHANISM.

Application filed May 21, 1926. Serial No. 110,666.

My invention relates to oil consuming heaters of the general class in which the height of the flame is controlled by a change in height of the level of oil in an oil supply well with respect to the wick of a burner connected to this well.

When such oil burners are used within enclosures, it is often desirable to have the oil well located outside of this enclosure, therefore permitting both a replenishing of the oil supply and an adjusting of the height of the flame without admitting an undesirable amount of air into the enclosure. For example, in a chicken brooder heated by an oil burner, any opening of the usual curtaining on the brooder hood would expose the delicate chicks to drafts, so that it is highly desirable to have an arrangement whereby the height of the flame in the oil burner can be controlled from outside the brooder hood.

An effective arrangement for this purpose was shown in the Landgraf Patent No. 1,531,236 of May 24, 1925, in which the oil font of the burner is connected by a substantially U-shaped pipe to the bottom of the oil well, this oil well being disposed outside of the brooder hood and supported by a cam-ring which can be moved so as to raise or lower the oil well. While this arrangement affords a convenient control for the level of the oil at the burner and serves nicely for adjusting the initial height of the burner flame, further adjustments are needed to prevent an undue heating of the air under the brooder hood, thereby requiring the services of a vigilant attendant.

My present invention aims to provide an arrangement whereby the effective height of the oil in the font of the burner will be automatically adjusted in response to variations in temperature within the brooder hood, thereby eliminating the need of all attention (after the burner is lit and the oil supply well is initially adjusted in height) except for replenishing the supply of oil to the oil well.

Generally speaking, I accomplish this purpose by supporting the oil burner so that its height is regulated by a thermostat under the brooder hood, and by arranging this au-

tomatic control so that it will not interfere with a manual regulation of the height of the oil supply well. In the drawings,

Fig. 1 is a fragmentary central, vertical and longitudinal section through an automatically regulated oil-burning brooder embodying my invention, with the oil burner and thermostatic regulator in elevation.

Fig. 2 is a plan view of the same.

Fig. 3 is an enlarged vertical section taken along the line 3—3 of Fig. 2.

Fig. 4 is a section similar to the right-hand portion of Fig. 1 but showing the cam-ring and the lower part of the oil container in elevation.

In the illustrated brooder, the brooder hood (or hover) 1, which is supported by legs 2, houses an upright drum 3 provided with perforations 4 through which air can enter the drum. An inverted channel 5 rigidly connects this drum with a second upright drum 6 disposed outside the brooder hood, and this outer drum 6 carries pins 7 projecting radially into it for supporting a cam-ring 8. This ring in turn supports the flange of a cup-shaped oil well 9 in which a supply of oil is maintained by an inverted oil jar 10 which is supported by the mouth of the said oil well.

The bottom of the oil well 9 opens into one shank of a substantially U-shaped oil pipe 10 which extends through the channel 5 and which has its other shank connected to the bottom of the oil font 11 of the oil burner, thereby supplying oil to a wick 12. The oil font 11, which supports the usual annularly partitioned draft chamber 12, is mounted so that it can rock on a pivoting axis transverse of the axis of the channel 5, thereby permitting a raising and lowering of the oil well 9 without materially bending the oil pipe or straining the connection of this pipe to the burner.

To permit a thermostatic regulation also, I provide means whereby the thermostat controls the height of this pivoting axis. For that purpose, I am showing a rigid stem 13 depending from the burner font 11 and connected to one arm of a lever 14 by a pin 15 which affords the said pivoting

axis. The lever 14 is pivoted on a stationary support in the form of a riser 16 on a base piece 17 secured to the drum 3 by screws 18 which also fasten a bracket 19 to the outside of this drum. The other arm of the lever 14 projects through a slot in the drum 3 and is connected by a link 20 to the inner end of a control arm 21 disposed below the bracket 19, and the other end of the control arm is supported from the outer end of the bracket by a bolt 22 which extends loosely through the control arm to allow the latter to pivot on the nut of the bolt.

Interposed between the said bracket and the control arm are thermally expansive means for moving this arm so as to move the lever 14 in one direction, namely against the action of gravity which causes the weight of the oil burner to overbalance the weight of the control arm 21 and hence tends to lower the burner and to raise the control arm. To secure a powerful action, I desirably employ two socalled thermostatic wafers for this purpose, placing them side by side as shown in Fig. 2, each wafer being a sealed metal chamber 23 containing ether or the like and having a stem 24 projecting through the control arm to prevent a lateral shifting of the position of the wafer. Then I initially adjust the bolt 22 so that the weight of the burner only slightly overbalances the downward pull of the link 20, thereby making the control sensitive.

When the heater is not operating, the cam-ring 8 is in its lowermost position of Figs. 1 and 4, so as to bring the level of the oil 26 in the well 9 below the bottom of the wick in the burner font. In starting the burner, the cam-ring is rotated to raise the oil well 9, thereby raising the level of the oil correspondingly in the burner font 11 so that the wick can be lit, and the cam-ring is then adjusted in position to provide the desired maximum height of the flame.

When the air under the brooder hood (or hover) 1 warms up, the evaporation of the ether in the thermostatic wafers expands these wafers, so that they rock the control arm 21 about the nut of the bolt 22 and to pull the link 20 downward, thereby causing the lever 14 to raise the burner so as to reduce the extent to which the wick dips into the oil. This decreases the heating and, as the temperature of the air under the hood falls, the pressure within the thermostatic wafers is reduced so that the prepondering weight of the burner lowers the latter against the resistance of the downward pressure of the thermostatic wafers on the control arm. By suitably adjusting the bolt 22, I can readily make the resulting regulation so sensitive as to maintain a substantially uniform temperature under the brooder hood. Hence the only attendance required is the manipulating of the cam-ring (which

can be moved rotationally by a handle 26 projecting through a spiral slot in the outer drum 25, as shown more in detail in the said Landgraf patent) when the burner is to be lit or extinguished, and the occasionally replenishing of the oil in the oil jar 10.

To prevent an undue compressing of the thermostatic wafers, I desirably provide a stop for limiting the downward movement of the burner, such as a stop bracket 27 bolted to the drum 3 and having an upper horizontal portion 27^A adapted to engage some part rigidly associated with the burner, such as the upper end 13^A of the stem 13 which is fastened to the burner. However, I do not wish to be limited to this or other details of the construction and arrangement above disclosed, as many changes might obviously be made without departing either from the spirit of my invention or from the appended claims. Nor do I wish to be limited to the use of my invention in connection with a brooder.

Neither do I wish to be limited to the illustrated cam-ring arrangement for controlling the height of the oil in the oil well (or effective oil supply,) or even to the inclusion of any means for varying this height, since my novel thermostatic control will obviously afford the needed automatic regulation if the level of oil at this supply well is stationary at a suitable height.

I claim as my invention:

1. In an oil-burning heater, a burner, a supporting element upon which the burner is pivoted, an oil supply connected to the burner, means for raising and lowering the oil supply with respect to the burner, and thermostatic means for regulating the height at which the pivoting portion of the supporting element is disposed.

2. A heater assembly as per claim 1, in combination with means for limiting the downward movement of the burner.

3. In an oil-burning heater, a burner, a lever supporting the burner, an oil supply connected to the burner, manually operable means for raising and lowering the oil supply with respect to the burner, and thermostatic means for moving the lever so as to raise or lower the burner without varying the height of the oil supply.

4. In an oil-burning heater, a lever, a burner pivoted on one arm of the lever, a constant level supply connected to the burner, manually operable means for varying the height of the oil supply relative to the burner, a thermally expansive member, and means connecting the said member with the lever to raise the first named arm of the lever with a rise in temperature of the thermally expansive member.

5. In an oil heater, a stationary pivot base, a lever pivoted thereon, a stationary arm, a movable arm adjacent to the station-
